(57) **CLAIM**

The ornamental design for a sequencing device as shown and described.

DESCRIPTION

FIG. 1 is a left side perspective view of a sequencing device showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a right side perspective view of a sequencing device having multiple doors opened showing the claimed design;

FIG. 9 is a front view thereof;

FIG. 10 is a rear view thereof;

FIG. 11 is a right side view thereof;

FIG. 12 is a left side view thereof;

FIG. 13 is a front view of a sequencing device having a lower door opened and an upper door closed showing the claimed design;

FIG. 14 is right side view thereof;

FIG. 15 is a left side view thereof;

FIG. 16 is a front view of a sequencing device having an upper door opened and a lower door closed showing the claimed design;

FIG. 17 is right side view thereof; and,

FIG. 18 is a left side view thereof.

The broken lines in the Figures are included for the purpose of illustrating portions of the sequencing device and form no part of the claimed design.
